CABLE-RAISING DEVICE

Application filed August 28, 1929. Serial No. 388,959.

This invention relates to apparatus for use in connection with cable cars and the like, and is illustrated herein as embodied in a device adapted to raise a cable to enable it to be gripped by a clamp carried by the car.

In the use of cable cars, it is customary to provide a continuously moving cable and to equip the car with mechanism for releasably engaging the cable. With a car equipped in this manner, it is customary to disengage the clamp mechanism from the cable when it is desired to stop the car or to switch it from a main track to another track leading therefrom. Thus, when the cars are switched they must be disengaged from the cable on the main track and then later engaged with a similar cable which carries them along the other track.

In view of the fact that the clamp for engaging the cable is normally disposed above the cable when disengaged therefrom, it will be appreciated that to bring about proper engagement either the clamp must be lowered or the cable must be raised. The clamp mechanism is generally, owing to its characteristics of construction, carried by the car in such a manner that it cannot be raised and lowered, and it is accordingly customary to provide means for raising the cable at desired points to permit engagement therewith of the clamp.

Heretofore, the devices for raising the cable to permit it to be engaged by the clamp have generally comprised a frame work that is adapted to be associated with the track sections at the desired points, and a roller carried by the frame work for engaging and raising the cable. Owing to the continual pounding of the cars, it has been found necessary to secure the frame work fixedly to the track and heretofore this has been done by means of rigid members, such as bolts, rivets, etc., that constitute permanent fastenings. This manner of securing the frames in place is subject to a number of faults. In the first place, the permanent fastenings are apt to be broken in which event their replacement is an arduous task, and in the second place, it is quite often

desirable to move the frames from point to point, according to where it is desired to release and reengage the car with the cable, and a solid and permanent fastening is an obvious obstacle to any such plan.

In view of the foregoing considerations, it is an object of the present invention to provide a cable raising device which may be releasably secured to a track section. An important feature of the invention which is conducive to the accomplishment of the recited objects consists in the provision of an elongated frame work carrying a cable raising roll and being provided with a plurality of members for releasably engaging the track rails. In the illustrated embodiment of the invention, the members comprise presser plates that engage beneath the heads of the rails, to prevent vertical displacement of the frame, and are actuated by means of toggle joints.

Other objects and features of the invention will become apparent from a reading of the following specification in the light of the accompanying drawings, in which—

Figure 1 is a top plan view showing a cable raising device constructed in accordance with the present invention;

Figure 2 is a bottom plan view of the device disclosed in Figure 1; and

Figure 3 is an end view of the device shown in Figure 1.

Turning to the drawings, the reference numerals 10 and 12 indicate the rails of a track over which a cable car is adapted to run and the reference numeral 14 indicates the cable that extends midway between the rail sections. As heretofore pointed out, it is necessary to raise the cable at certain desired points to permit it to be engaged by a clamp that is carried by the car and to this end it is customary to provide a frame work 16 having a cable raising roll, or other suitable member, 18 carried thereby.

In the illustrated embodiment of the invention the frame comprises a plurality of spaced angle irons 20, 22 that carry the roll 18 and are connected by means of suitable fasteners 24, 26 to a plurality of transversely extending frame members 28 and 30. These frame mem-

bers are connected at their outer extremities to spaced, elongated, shoes 32, 34 that are adapted to be disposed upon the top surfaces of the rail sections to provide a suitable track over which the wheels of the cable car pass as the latter moves over the cable raising device. Shoes 32 and 34 are, as indicated in Figures 2 and 3, provided with downwardly depending lugs 36 and 38 that engage the outside faces of the rail sections and tend to maintain the cable raising device in proper position.

To the end of cooperating with the lugs 36 and 38 in holding the frame of the cable raising device in a fixed position in which it is releasably engaged with the rail members 10 and 12 the frame is provided at its opposite ends with a plurality of spaced presser plates 40 and 42 that are adapted, by means of toggle links 44 and 46 and an operating handle 48, to be moved into clamping engagement with the inner faces of the rail sections. By means of such a provision the frame may be releasably clamped in place at any desired point along the track and the means effecting the clamping are sufficiently flexible that they will not break owing to the repeated pounding of the car over the shoes 32 and 34.

Although the invention has been described herein with particular reference to cable cars, it is to be appreciated that it may be employed in analogous organizations, and it is likewise to be understood that changes and modifications may from time to time be made in the illustrated embodiment of the invention without departing from the scope thereof as set forth in the appended claims.

Having thus described our invention, what we claim as new and desire to secure by United States Letters Patent, is:

40. 1. A device for use in raising a cable to a point where it can be grasped by a cable car, comprising, in combination, a frame adapted to rest upon the track rails over which the car runs, a cable engaging instrument mounted on said frame, and means for releasably affixing the frame to the track rails.

50. 2. A device for use in raising a cable to a point where it can be grasped by a cable car, comprising, in combination, a frame having a cable engaging instrument mounted thereon, said frame being adapted to be placed between the rails of the track over which the car runs, and means for applying pressure to the inner walls of the rails, at separated points, to releasably affix the frame to the track.

60. 3. A device for use in raising a cable to a point where it can be grasped by a cable car, comprising, in combination, an elongated frame adapted to rest upon the track rails over which the car runs, a cable guide mounted thereon, and means carried at opposite ends of the frame for releasably affixing the latter to the track rails.

55. 4. A device for use in raising a cable to a

point where it can be grasped by a cable car, comprising, in combination, a frame having a cable engaging instrument mounted thereon, and a lever actuated clamp for releasably affixing the frame to the track over which the car runs.

5. A device for use in raising a cable to a point where it can be grasped by a cable car, comprising, in combination, a frame having a cable engaging roll mounted thereon, a plurality of members carried by the frame and adapted to engage the rails of the track over which the car runs, and means for actuating the members to move them into and out of engagement with the rails.

6. A device for use in raising a cable to a point where it can be grasped by a cable car, comprising, in combination, an elongated frame having a cable engaging roll mounted thereon, and a plurality of toggle operated clamps carried at opposite ends of the frame for releasably affixing the frame to the track over which the car runs.

Signed at Duluth, Minn., this 15th day of August, 1929.
